H. STANLEY.
Cooking Stove.

Patented Dec. 17, 1832.

Henry Stanley

91

The Schedule referred to in these Letters Patent and
making part of the same.

To all whom these presents shall
come (existing) I Henry Stanley,
of Boston, in the County of Suffolk and State of Mass-
sachusetts, inventor of a new and useful improvement in
the revolving Cooking Stone to call, and the following is a
description of my said invention and improvement, it
being an amended specification for a new patent in place
of one surrendered on account of its defective specification
consisting of a fire room suitable to the size of the stone
and the stone may be of such size as to suit the purchaser,
The fire room may be differently constructed for different kinds
of fuel. If it is designed for Anthracite or other coal the
fire room should be lined with fire bricks and be furnished
with suitable grates. The fire room is formed of four cast iron
plates set upon and partly covering another cast iron plate
called the hearth or bottom; the back plate is then introduced
for wood is made of two parts divided at or near the middle
perpendicularly, and when intended for coal the back plate
is divided at or near the middle horizontally, or length-
wise. The lower division is placed about one inch within
the upper division and has a projection attached to the
whole length of its upper edge, and running ^{back} so as to form
a support for the upper division and also for the fire brick
which forms the back of the furnace. The upper edge of the
plate is exposed to the action of the fire within the furnace
for the purpose of increasing the quantity of heat in the
lower part of the fire room, or roaster when placed in the
rear of the back plates. The distinctive effects of the heat
upon the lower division requires that it should be

occasionally removed and to avoid the expense and trouble of removing the entire plate an opening is made at or near the upper edge of about two-thirds the length and one-third the width of the plate. This opening is filled with another moveable plate which may be removed and renewed at pleasure. In the hearth or bottom plates found a ditch or ash-pit partly covered by the fire room, and partly by a sliding plate which acts as a damper and regulates the heat. A large circular plate is placed over the fire room, in such a manner that a segment of about one-third the diameter of the circular plate is ^{circular} left in the fire room. This circular plate is covered by another plate in diameter something larger which stands the top on top of the stove the latter being raised above the former about one inch by risers forming a groove on the upper side of the lower circular plate and a corresponding rise on the under side of the upper circular plate forming a tongue to answer to said groove on which tongue the upper plate rests.

On the center of the under plate is a small elevation in the form of a cone with a perpendicular orifice into which a pinion projects from the upper plate in order to fit the center of the revolution. The evolution is caused by a crank or pinion. The cogs of the pinion work in corresponding ones attached to the under side of the upper plate near the edge which projects beyond the riser. Through the lower circular plate and directly over the fire room is an opening through which the heat is conducted. The dimensions of the opening being described by that part of the fire room which comes within the circular room upon the edge of the under circular plate.

Opposite the fire room and through the same plate is another opening through which the smoke passes into the lining flues to which the pipe is attached to convey the smoke to the chimney.

Dec 17, 1832

The top is provided with holes of sufficient size in number and dimensions to correspond with the size of the stone. These holes are to receive boiles and other working utensils or articles to be heated and are raised by means of rivets or collars from 2¹/₂ to 3 inches deep and converging toward the top for the purpose of exposing a greater surface of the boiler or other articles to the action of the heat in its passage from the fire room to the dining floor, and also for the like purpose as well as for convenience in casting and to strengthen the plate. Smaller flues on the under side of the cap or top plate leading from boiler to boiler, and circuitously to the dining flue, as shown in the drawing originally deposited in the Patent Office with this paper as a further illustration of the parts allowed to in this Specification. —

In this roasting, it may be done in an open oven constructed in the back part of the stone in the common way, or by two reflectors suitably constructed and placed upon the top and in front of the stone, and in rear of the fire room and under that part of the circular plate which is not occupied by the fire room. Summary. — I claim as my invention the combination of any one or more of the following particulars in the said stone as above described when combined with a revolving top plate. First, the flues in the revolving top plate. Second, the rivets or collars surrounding the working utensils. Third, the groove as above described, and the tangs on which the upper plate rests. Fourth, the road and pinion used to cause the revolution of the top plate. — But I do not claim as my invention any one of the above described parts or combination of them, independently of their connection with a revolving top plate. Neither do I claim the invention of a revolving top plate.

Witness, Thomas D. Moore, (Hand of Moore) Marcellus Thompson
